UNITED STATES PATENT OFFICE.

CHARLES E. WAKE, OF KIRWIN, KANSAS, ASSIGNOR OF ONE-HALF TO
CARLTON S. INGERSOLL, OF SAME PLACE.

ACETYLENE-GAS GENERATOR.

SPECIFICATION forming part of Letters Patent No. 634,075, dated October 3, 1899.

Application filed May 22, 1899. Serial No. 717,780. (No model.)

To all whom it may concern:

Be it known that I, CHARLES E. WAKE, a citizen of the United States, residing at Kirwin, in the county of Phillips and State of Kansas, have invented a new and useful Acetylene-Gas Generator, of which the following is a specification.

My invention relates to improvements in acetylene-gas generators of that class where-
10 in gas is produced by a liquid attacking a solid, such as calcium carbid; and the objects in view are, first, to provide improved means for regulating the admission of water to a generator in a manner which will wholly ob-
15 viate flooding of said generator on exhaustion of the carbid therein, and, secondly, to provide improved vent devices operable to automatically permit the escape to the out-
20 side of a building of the surplus volume of gas contained in the floatable bell.

With these ends in view the invention consists in the novel construction and arrangement of parts, which will be hereinafter fully described and claimed.

25 In the drawings, Figure 1 is a perspective view looking at the front side of the apparatus. Fig. 2 is an elevation from the rear side of the apparatus, showing the vent devices. Fig. 3 is a vertical section of the generator. Fig. 4 is an enlarged detail view of the wa-
30 ter-valve devices.

The same numerals of reference are used to indicate like and corresponding parts in each of the several figures of the drawings.

35 The generator 10 of my apparatus is constructed to provide a water-seal chamber 11, in which is immersed a gas-bell 12, that is confined in place by a suitable form of clamp, (indicated at 13.) The water is supplied to 40 this generator from an elevated tank 14 by means of a water-pipe 15, and this water-pipe is provided with a horizontal branch 16 be-
45 tween the two vertical end portions thereof. One end of said water-pipe is extended down-
wardly to form a trap 15^a, one branch of which is carried through a seal-chamber in the dou-
50 ble-walled tank of the generator 10 in a po-
sition to supply the water over the carbid which is contained within the generator. (See Fig. 3.) The other end of said pipe 15

is united to the lower part of the elevated tank 14, all as clearly shown by Fig. 1. The horizontal part 16 of the water-pipe is pro-
55 vided with the valves 17 18, which are spaced at a suitable distance from each other, and these valves are operated by devices which will be hereinafter described to automatically open or close the valves simultaneously for regulating the admission of water to the gen-
60 erator.

The gas is conveyed from the generator by means of a pipe 19, which has a vertical branch 20, that is carried or extended through the seal-chamber 11 of the generator, and the ex-
65 tremity of this pipe-branch 20 opens into the upper part of the generator, so that the gas will pass from the latter through the branch 20, whereby the gas is partly cooled as it passes through that part of the pipe which is im-
70 mersed in the water contained in the seal-
chamber 11 of the generator. At the point where the pipes 19 20 meet each other they are united by a cross-coupling 21, and this coupling has a cock 21^a attached thereto for the purpose of discharging any water of con-
75 densation which may accumulate in the pipes 19 or 20. The gas-pipe 19 is extended up-
wardly to the tank 14 for union with one end of the cooling-coil 24, which is contained or 80 immersed in the contents of said tank, and from the other end of this coil 24 leads a pipe 25, which is conducted to the bottom of the gas-
85 meter-tank 27, said pipe 25 having a branch pipe 26, which extends vertically through the water contained in the tank 27. A floatable 90 gas-bell 28 is inverted into the water-tank 27, and to this gas-bell is discharged the gas which passes through and is cooled by the coil 24 and thence conveyed by the pipes 25 26 from said coil to the bell 28. A trip-rod 29 is fastened in any suitable way to the head of the floatable bell 28, and at a point intermediate of its length this trip-rod is notched to form a shoulder 30.

One of the valves in the branch 16 of the 95 water-pipe, preferably the valve 17, has a lever 31 secured fast thereto, and the free end of this lever is provided with a weight 32, which may be fastened adjustably to said lever. The lever is extended or carried beyond 100

the valve to which it is attached, and its free upper end is formed or otherwise provided with a fork 33. The forked end of the lever is disposed in such relation to the trip-rod 29 as to receive the lever between the branches thereof, so that the trip-rod is slidably confined by the fork in operative relation to the weighted lever, and on the downward travel of the bell and the trip-rod therewith the shoulder 30 of said rod is adapted to impinge against one branch of the fork 33 for the purpose of moving the lever 31 against the ponderosity of its weight, so as to open its valves more or less.

15 The two valves 17 18 are connected together for simultaneous operation by providing the arms 35 36 on the movable valve elements, and these arms are connected operatively by a link 37, which has its respective 20 ends pivoted to the arms, whereby a movement of the valve 17 under the play of the lever 31 in either direction will actuate the link 37 to correspondingly move the other valve 18. The employment of the two valves 25 connected by the link for simultaneous operation is an important feature of my invention, because the valves may be set or adjusted in such a way as to regulate to a nicety the volume of water which may flow through 30 the pipe 15 16 to the generator, and the trip-rod and lever 31 provide an efficient means by which a slight movement of the floatable bell 28 is communicated to the valves either to partly open the same, to fully open said 35 valves to secure a large supply of water to the generator, or to wholly cut off the water-supply. According to my invention I contemplate the adjustment of the valves so that one will be opened to a greater extent than the 40 other, and thus the supply of water in the branch pipe 16 may be regulated within certain limits, according to the demands of the generator in the production of acetylene gas.

45 A vent-pipe 38 has one end coupled to the gas-pipe 25 26 by the union 38^a, (see Fig. 1,) while the other part of the vent-pipe is carried or extended to the outside of the building. In this vent-pipe is provided a valve 39, to which is attached an elbow-shaped lever 40, 50 having one arm 41 thereof arranged to impinge against the service-pipe 46 in order to limit the movement of the lever in one direction when the valve is moved to its closed position. The other arm of this lever, which controls the vent-valve, is provided with a longitudinal slot 42, and to the free extremity of said lever is connected a weight 43, which tends to move the lever normally to a position where the vent-valve closes the pipe 38, 55 and the arm 41 abuts against the service-pipe 46. Through the slot in the weighted arm of the lever passes a trip-rod 44, which has its upper end fastened to the head of the floatable bell, and the lower end of said trip-rod 60 is provided with an angular foot 45, which is adapted to bear against the lever for raising the weighted arm thereof in order to open the

vent-valve thereof when surplus gas accumulates in the bell 28. The service-pipe 46 is provided with a branch which is carried 70 through the body of water contained in the tank 27 in order to convey the gas from the gasometer to the burners.

In operation a carbid vessel containing a suitable supply of calcium carbid is placed in the generator and the bell thereof is closed and fastened in place, so that the bell is immersed in the seal 11 to minimize the escape of gas from the generator. As the floatable bell settles in the tank the trip-rod moves downwardly therewith, and the shoulder 30 of said trip-rod impinges against one of the branches of the fork 33, thereby turning the lever 31 and operating the valve 17 and link 37 so as to open the two valves 17 18. Water 85 flows from the tank 14 through the pipe 15 16 to the generator to attack the carbid and produce acetylene gas, which flows through the pipe 20 19 to the cooling-coil 24 and thence through the pipe 25 26 to the floatable bell. 90 As the gas accumulates in the bell the latter is lifted to raise the trip-rod 29 and withdraw its shoulder from the lever 31, thus permitting the weight to move said lever for the operation of the valves 17 18 in a manner to shut 95 off the flow of water. This operation is continually intermittently and automatically according to the consumption of gas at the burners; but when the carbid becomes exhausted the bell and the trip-rod continue to travel in a 100 downward direction until the lever-fork will assume a position where it will slip clear of the shoulder 30 on said trip-rod, whereupon the weight of the lever acts to move the same to the position for closing the two valves, thus 105 effectually cutting off the supply of water and preventing the carbid from being flooded by an excessive water-supply. The trip-rod 44, which operates the vent-valve lever, is free to travel with the gas-bell within certain limits 110 and under normal conditions without permitting its foot 45 to operate the vent-valve; but the accumulation of an undesirable volume of gas within the bell 28 will lift the rod upwardly for the foot 45 to lift the lever 40 and 115 open the vent-valve 39, thus permitting the gas to pass through the pipe 38 until the bell descends to a position which permits the foot 45 and lever 40 to close the valve 39.

Changes in the form, proportion, size, and 120 the minor details of construction within the scope of the appended claims may be resorted to without departing from the spirit or sacrificing any of the advantages of this invention.

Having thus described the invention, what 125 I claim is—

1. In an acetylene-gas apparatus, the combination with a generator and a water-supply pipe therefor, of the connected valves attached to said water-supply pipe and adapted 130 for simultaneous operation, a lever fast to one of said valves to normally move the same to closed position, and a trip-rod loosely movable against said lever for a portion of its

length and having a shoulder arranged to strike the lever for positively moving the latter to a position for opening said valves.

2. In an acetylene-gas apparatus, the combination with a floatable bell, a generator, and a water-pipe to said generator, of the valves attached to said water-pipe and provided with the arms, a link pivoted to said arms for simultaneously operating both valves, a weight-
10 ed lever attached to one valve and having a fork at its free extremity, and a trip-rod connected to the bell and slidably fitted in the fork of said lever, said trip-rod having a shoulder arranged to ride against the lever-fork to positively actuate the latter on the descent of the bell, substantially as described.

3. In an acetylene-gas apparatus, the combination with a gasometer and a generator, of a vent-pipe having a valve therein, a weight-
20 ed angle-lever attached to said valve and provided with a slot in one of its members, the opposite member of said lever having the terminal thereof in impinging relation to an adjacent stationary part, and a trip-rod connected to a movable part of said gasometer and slidable through the slot of said angle-lever, said trip-rod having a foot branch to lift said lever for opening the vent-valve.

25 4. In an acetylene-gas apparatus, the com-

bination with a gasometer having a service- 30 pipe and a generator, of a vent-pipe provided with a valve, a double-armed lever attached to said valve for one arm thereof to impinge against the service-pipe and having the slot and weight on its other arm, and a trip-rod 35 attached to the bell and slidably fitted in the slotted arm of the lever, said trip-rod having a foot to impinge against the lever, substantially as described.

5. In an acetylene-gas apparatus, the combination with a generator and a water-supply pipe therefor, of valves attached to said supply-pipe and adapted for simultaneous operation and provided with connected arms, a lever fast to one of said arms and having a 40 weight at one extremity, and a trip-rod loosely movable against the opposite extremity of said lever and having a shoulder to strike the lever to move the latter and positively open the valve against the resistance of the weight. 50

In testimony that I claim the foregoing as my own I have hereto affixed my signature in the presence of two witnesses.

CHARLES E. WAKE.
